[57] CLAIM

The ornamental design for a fixed blade knife, as shown and described.

DESCRIPTION

FIG. 1 is a left-side elevational view of a fixed blade knife, the right-side elevational view being identical thereto;

FIG. 2 is a top view thereof;

FIG. 3 is a bottom view thereof;

FIG. 4 is a front elevational view thereof from the point end of the fixed blade knife; and,

FIG. 5 is a back elevational view thereof from the butt end of the fixed blade knife.

FIG. 1

FIG. 2

FIG. 3

FIG. 4

FIG. 5
